**CONTAINERS FOR STORING GOBLETS, GLASSES
AND OTHER SIMILAR PRODUCTS**
Seymour Schaefer, Evanston, Ill., assignor, by mesne
assignments, to Aaron H. Plotzker, Skokie, Ill.
Filed Dec. 31, 1962, Ser. No. 248,496
2 Claims. (Cl. 150—52)

This invention relates to a container for storing goblets, glasses, and other similar products.

Due to the fragile nature of glassware, such as goblets and the like, they have to be handled very carefully when they are stored away between uses. Even when stored away in a cabinet there is always danger of chipping and breaking when the glasses or goblets are handled or moved adjacent each other. This invention therefore provides means whereby goblets, glassware and the like may be put into containers wherein the goblets are protected from contact or engagement with other goblets so that any breaking, chipping, cracking or the like is completely eliminated, and wherein they are enclosed to be kept clean for their next use.

Another object of this invention is to provide means for storing goblets and other like glassware wherein they may be readily removed when desired.

Another object of this invention is to provide a structure having the foregoing objects which is simple and inexpensive to manufacture.

Other objects will become apparent as this description progresses.

In the drawings:

FIG. 1 is a perspective view of the container in closed position, with the glass receiving compartments being enclosed therewithin.

FIG. 2 is an enlarged perspective view of same with the lid uncovered, showing the glass receiving compartments.

FIG. 3 is a perspective view of the pair of glass receiving compartments.

FIG. 4 is an enlarged sectional view taken on line 4—4 of FIG. 1, and

FIG. 5 is an enlarged sectional view taken on line 5—5 of FIG. 2.

The carrier or container for the plurality of glass receiving compartments or receptacles is generally designated by the numeral 10 and comprises a generally rectangular shaped box which may be formed of fabric, plastic, leather, or any other suitable material which is preferably flexible.

The carrier includes a generally rectangular shaped bottom wall 12 which is stitched as at 14 to a continuous vertical wall 16 which forms the side and end walls of the carrier. Supported on the bottom wall 12 is a strip of cardboard 18 which may be suitably covered by a sheet of fabric 20 for the purpose of providing a stiffened bottom wall. A generally rectangular shaped lid 22 formed of a flexible material has a strip of interlocking fastening elements 24 sewn thereto. Likewise, the upper edge of the vertical wall 16 has a strip of interlocking fastening elements 26 secured thereto so that a slide fastener 28 can be moved between the interlocking elements to close same, as is well understood in the art. The lid 22 is permanently attached to the rear end of the vertical wall 16 by a connecting strip 30 so that when the lid is folded back it will always remain attached to and be part of the container, as shown in FIG. 2, and when closed the container is as shown in FIG. 1.

Supported within the container are a plurality of glass receiving members generally designated by the numeral 32. Each member 32 is formed that it shapes to provide two contiguous glass receiving compartments 34. Said glass receiving members are identically formed and six of such members are shown in FIG. 2, one of said members being best shown in FIG. 3. Each member 32 is formed of a continuous strip of material 36 which would be of generally rectangular shape when laid out before being preshaped as shown in FIG. 3. The strip is of a length so that it forms the two glass receiving pockets or compartments 34 and 35 and is of a height to extend slightly above the top of the glass or goblet 39 adapted to be positioned therewithin, as shown in FIG. 4.

10 The rectangular strip 36 is formed of a pair of flexible fabric or like material coverings 38 and 40, between which is interposed a stiffening member 42, all of which are stitched together as at 44 along the border edges thereof to form an integral rectangular shaped strip 36. 15 The stiffening member 44 will provide body for the strip, yet the strip is sufficiently flexible to permit its collapsing and expanding when in its finished shaped form, and will have sufficient body to provide the protection desired.

20 The strip 36 is folded or shaped as shown in FIG. 3, 25 in which the opposite ends of the strip indicated by the numerals 46 and 48 are turned inwardly and positioned approximately centrally of the length of the strip. In this position the end 46 of the strip will lie against the center of one side of the strip, with the opposite end 48 lying 30 against the opposite side and center of the strip, all in a contiguous relationship. With the strip thus shaped, the opposite ends 46 and 48 are secured to the center of the strip by means of eyelets 50 along the upper and lower edges of said strip. The configuration formed is 35 generally that of the numeral 8. Thus, it will be seen that each strip 36 forms a pair of glass receiving pockets or compartments 34 and 35, similar to that shown in FIG. 3. A plurality of such pairs of glass receiving pockets are positioned in the container as shown in 40 FIG. 2.

45 In a rectangular shaped carrier, I have found that six pairs of glass receiving compartments, making a total of twelve compartments or pockets, may be positioned therein, as shown in FIG. 2.

50 The pairs of glass receiving pockets are not attached to any portion of the container or carrier. These pairs may be collapsed if desired, however, they will assume the full shape shown in FIGS. 2 and 3 when a glass is positioned therein, as shown in FIG. 4, and each pocket will have a generally cylindrical shape. As shown, the glass is fully protected from coming into contact with any glass positioned in any other adjacent pocket.

55 It will be understood that various changes and modifications may be made from the foregoing without departing from the spirit and scope of the appended claims.

What is claimed is:

1. In a storage container of the character described for storing goblets, glasses and like articles of a fragile and readily broken material and the container has a vertical side wall secured between opposite end walls; the herein invention consisting of an article receiving member adapted to be installed vertically oriented in said container between said end walls, said member comprising, a continuous, generally rectangular strip of flexible fabric material having a pair of opposite ends, said strip being folded intermediate said ends to locate said ends centrally of the length of the strip with each of said ends

abutting a different surface of the strip whereby said strip has a substantially 8-shaped configuration, said ends being secured to the strip to provide a pair of separate article receiving pockets of generally cylindrical configuration open at opposite ends thereof, the width of said strip being received selected to be greater than the article to be received in a pocket, said member capable of being collapsed to a substantially flattened configuration when not loaded with the articles contiguous one to the other, each of said ends being secured to the center of said strip along the upper and lower edges of said strip.

2. In a structure as defined in claim 1 in which the said strip is formed of a pair of flexible fabric sheets disposed about an interposed stiffening sheet sewn to-

gether along the marginal edges thereof, said ends having grommet fasteners securing same to the strip top and bottom, each grommet extending through both ends.
